ABSTRACT OF THE DISCLOSURE

Process for preparing trialkylamines from a mixture of alkylbromides containing alkyl groups of from 10 to 20 carbon atoms, dialkylamines containing from 1 to 3 carbon atoms, and water, the molar ratio of dialkylamines to alkylbromides being in excess of about 8:1 by reacting the alkylbromides with the dialkylamines for 2 to 7 minutes at a temperature of from 100° F. to 190° F. and thereafter heating the reaction product to a temperature of from 275° F. to 375° F. for from 4.5 to 12 minutes.

This invention relates to a process for the preparation of tertiary amines by aminating alkylbromides.

One outgrowth of the increased use of amine oxides as synthetic detergents has been the need in the detergent industry to find an improved method of preparing a relatively pure oxidizable tertiary amine product. Such amines can be produced by aminating an alkylbromide.

An important source of alkylhalides is via a reaction between alpha olefin raw materials and, either, a halogen or a halide acid. By this reaction, the α -olefins are converted to both primary alkylhalide, e.g., 1-bromoalkane, and secondary alkylhalide or internal halide, e.g., 2-bromoalkane. With free radical addition processes, about 90% to 95% of an essentially straight chain α -olefin raw material can be converted to primary straight chain alkylhalides, e.g., alkylbromides. α -Olefin raw materials also contain small amounts of branched chain olefins. These branched chain olefins are converted to branched chain alkylbromides by a free radical bromination reaction. In addition, the reaction product will also contain small amounts, i.e., about 5% of internal bromides.

Processes for aminating mixtures of alkylbromides of the type just described presented several problems. One of the most serious was that substantial quantities of quaternary ammonium compounds were formed along with the desired tertiary amine compounds. The quaternary ammonium compounds constitute impurities in the end product when it is to be used in the preparation of detergents, e.g., the amine oxide. The formation of the quaternary ammonium compounds is costly, yet these compounds are inert components in the amine oxide synthetic detergent. It can readily be appreciated that the formation of these quaternary ammonium compounds is undesirable and if possible should be avoided. In some cases, when the quaternary level becomes too great from the practice of known processes, the formulator has no choice but to separate the quaternary ammonium compounds from the tertiary amines at considerable expense. Additionally, it has been found that branched chain bromides and secondary bromides require an inordinately long reaction time to completely react with the various dialkylamines during an amination reaction at the lower temperatures at which the primary alkylbromides react rapidly. If higher temperatures are utilized to shorten the reaction time, undesired ammonium compounds are formed. Regeneration of olefins from the secondary alkylbromides is also often a problem.

Accordingly, it is a primary object of this invention

2

to provide a process for preparing tertiary amines, i.e., trialkyl amines, by aminating alkylbromides comprising major portions of primary alkylbromides and minor portions of branched chain and secondary bromides, which process reduces or eliminates problems ordinarily connected with such amination. It is a further object of this invention to provide a process of preparing tertiary amines which is rapid and continuous and which results in minimal regeneration of α -olefins and quaternary ammonium compound formation. Another object of this invention is to provide a process as described above which insures substantial completeness of the reaction.

Still further objects and the entire scope of applicability of the present invention will become apparent from the detailed description given hereinafter. It should be understood, however, that the detailed description and specific examples, while indicating preferred embodiments of the invention, are given by way of illustration only since various changes and modifications within the spirit and scope of the invention will become apparent to those skilled in the art.

It has now been discovered that the foregoing objects of the present invention for preparing a trialkylamine are attained by a process comprising the steps of

25 (1) Preparing a reaction mixture containing an alkylbromide, said alkylbromide being comprised of a major portion of straight chain primary alkylbromides and a minor portion of straight chain secondary alkylbromides and branched chain primary alkylbromides, wherein the 30 alkyl group of said alkylbromides contains from about 10 to about 20 carbon atoms; and a dialkylamine-water solution comprising a dialkylamine wherein the alkyl groups contain from 1 to about 3 carbon atoms; said dialkylamine-water solution containing from about 5% to 35 about 20% water by weight; the molar ratio of said dialkylamine to said alkylbromide in said reaction mixture being in excess of about 8:1;

(2) Reacting said alkylbromide with said dialkylamine for from about 2 to about 7 minutes at a temperature of from about 100° F. to about 190° F. and under sufficient pressure to maintain said dialkylamine in a liquified state to form a reaction product;

(3) Thereafter heating said reaction product to a temperature of from about 275° F. to about 375° F. for from about 4.5 to about 12 minutes and under sufficient pressure to maintain said dialkylamine in a liquified state.

FIGURE 1 and FIGURE 2 are drawings showing time/temperature profiles characteristic of the amination reaction of the present invention.

50 In the first step of this invention, a reaction mixture comprising an alkylbromide, a dialkylamine and water is prepared.

The alkylbromide raw material is comprised principally of a mixture of straight chain and branched chain primary and secondary alkylbromides. By far the major portion of the alkylbromide raw material is straight chain primary alkylbromides making up from about 90% to 95% by weight of the alkylbromide raw material. A minor portion of the alkylbromide raw material is a mixture of from about 2% to about 5% by weight of straight chain secondary alkylbromide and from about 1% to about 4% of a branched chain primary alkylbromide. There can also be present in the raw material alkylbromide a very minor amount, i.e., less than 3% by weight, of an internal branched chain alkylbromide which is either a secondary or tertiary alkylbromide.

It is a significant discovery of the present invention that the straight chain secondary alkylbromides and the branched chain primary alkylbromides which make up the minor portion of the alkylbromide raw material have comparable reaction rates in the novel amination reac-

tion. Thus, for example, it has been discovered that a compound such as 2-bromododecane behaves more like 1-bromo-2-ethyl decane than like 1-bromododecane in the amination reaction described herein.

It is this feature which, in part, led to the unexpected discovery that an improved amination reaction required a time/temperature profile which represented a major departure from time/temperature profiles of prior art amination reactions. FIGURES 1 and 2 illustrate that time/temperature profiles which characterize typical continuous and batch processes performed according to the present invention. The drawings are deemed self-evident but it can be observed that each drawing shows two temperature levels, the first being considerably lower than the second. The first relatively low curve represents the temperature prevailing during the first reaction step, and the second elevated temperature curve represents the second reaction step. In both FIGURE 1 and FIGURE 2, there is a sharp inclined line indicating the end of a typical first reaction step and the initiation of a typical second reaction step. The limits and ranges both in time and temperature are critical, and although they have been mentioned above, they are described in more detail below.

In addition to the foregoing specifically mentioned alkylbromides which comprise the alkylbromide raw material, there can also be present minor amounts of paraffins, unreacted α -olefins, and the like at a level of up to about 4% by weight of the alkyl bromide without adverse effects. The α -olefins as well as the paraffins are essentially inert throughout the process and do not interfere with the reaction.

The alkyl group of the alkylbromide reactant of the initial reaction mixture can contain from about 10 to about 20 carbon atoms. In a preferred embodiment of the invention, the alkyl group contains from 12 to 16 carbon atoms. These various chain length alkylbromides can be utilized individually per se or in combination with each other in any proportion.

The alkylbromide raw material employed in the amination process of this invention can be prepared, as mentioned above, by the reaction of hydrogen bromides with unsaturated hydrocarbons, e.g., alpha-olefins. Ordinarily, if an unsymmetrical olefin is treated with hydrogen bromide, the hydrogen and the bromine add across the carbon-carbon double bond; the hydrogen attaches itself to the carbon atom bearing the greater number of hydrogen atoms and the bromine attaches itself to the carbon atom bearing the least number of hydrogen atoms. This mode of addition is termed the normal or Markownikoff addition, the product of which is a secondary bromide. The alkylbromide utilized in this invention should, as described above, contain a primary bromide as a major ingredient, e.g., 90% to 95% by weight. Primary bromides are formed by an addition process variously de-

noted as abnormal, anti-Markownikoff or free radical addition.

Several methods are known by which free radical addition can be effected. Various free radical promoters such as peroxides, e.g., hydrogen peroxide or acetyl peroxide, as well as compounds which tend to form peroxides when contacted with unsaturated compounds such as oxygen, air, or ozone can be utilized with hydrogen bromide and an α -olefin to effect free radical or anti-Markownikoff addition. It is also known that ultraviolet radiations can be used to promote or catalyze the abnormal addition of hydrogen bromide to unsaturated organic compounds. By such processes as well as processes described in copending commonly-assigned applications of Adrian Kessler, Ser. No. 333,575, and of Glen Wyness et al., Ser. No. 333,576, it is possible to produce alkylbromides for use in this invention which comprise a major portion of straight chain primary alkylbromides and a minor amount of straight chain secondary alkylbromides, and branch chain primary alkylbromides.

20 Many alkylamines. Liquified dialkylamines utilized in this process have alkyl groups containing from 1 to about 3 carbon atoms. The two alkyl groups of the amine molecule can consist of the same or different numbers of carbon atoms within 25 the specified range. The various amines, such as those listed below, can be used per se or in combination with each other in any amounts provided the essential molar proportions previously mentioned are adhered to.

Specific examples of dialkylamines suitable for use in this invention are the following: dimethylamine, diethylamine, dipropylamine, methylethylamine, methylpropylamine and ethylpropylamine. The preferred dialkylamine for this process is dimethylamine.

The following table illustrates several of the physical properties of the dialkylamines which are of importance in this invention.

TABLE I—PHYSICAL PROPERTIES OF DIALKYLAMINES

	Dimethyl- amine	Diethyl- amine	Dipropyl- amine
Molecular Weight.....	45.80	73.14	101.19
Melting Point, ° F.....	-141.0	-58.0	-39.3
Boiling Point, ° F.....	45.4	132.0	231.0
Density, gms./ml.....	0.6804	0.7108	0.7384
Solubility in Water, gms./100 ml.....	(1)	(2)	(2)

¹ Very soluble.

1 Very sol
2 Soluble.

As can be seen from the preceding table, some of the dialkylamines of this invention will not be in a liquified state at ordinary temperature and pressures. Others would 50 be volatilized at the temperatures utilized in this process unless the reaction takes place under sufficient pressure to prevent said volatilization. It is also apparent from the preceding table that this pressure will vary with the particular amine utilized in the process. When dipropylamine 55 is utilized in this process, a pressure as low as 75 pounds per square inch gauge is sufficient to maintain it in a liquified state. A correspondingly higher pressure of above about 350 pounds per square inch should be utilized in this process to maintain dimethylamine in a liquified state. 60 The upper pressure limitation is governed only by the strength of the reaction vessel and the amount of pressure that can economically be applied. Pressures over 3000 pounds per square inch are, however, not commercially feasible and this can be regarded as the upper limit. 65 When the preferred dimethylamine is utilized, the preferred pressure throughout the reaction system is maintained in the range of from about 350 pounds per square inch gauge to about 1200 pounds per square inch gauge. These pressures must be maintained throughout the entire 70 process to prevent volatilization of the dialkylamines.

In this process, it has been found to be advantageous to use a molar excess of liquified dialkylamine to react with the said alkylbromide to effectively reduce formation of the quaternary ammonium compounds as well as to insure almost complete reaction of the alkylbromide.

Molar ratios of dialkylamine to alkylbromide greater than about 8:1 have been found to be satisfactory in this process. At any molar ratio in excess of about 8:1, the formation of quaternary ammonium compounds is effectively reduced and the reaction is substantially complete. The upper limitation on the molar excess is governed primarily by the size of the reactor and the desired output of the tertiary amine. However, in a preferred embodiment of this invention, a molar ratio of from 12:1 to 18:1 is utilized.

Water is added as an essential ingredient to the reaction mixture in critical proportions. The addition of water serves the useful purpose of increasing the reaction rate of the amination process. However, if an excess of water is added to the dialkylamine and alkylbromide, two phases, an oil phase and a water phase, will form. Such a two-phase system substantially promotes the formation of the quaternary ammonium compounds and, thus, needs to be avoided. According to the process of the present invention, from about 5% to about 20% water by weight of the dialkylamine-water solution is utilized in this invention. In no instance, however, should water be added to the reaction mixture in such amounts as to form two phases as hereinbefore described. In a preferred embodiment of this invention, the water comprises from about 8% to about 15% by weight of the dialkylamine-water solution.

In a preferred embodiment of the present invention, water is introduced into the reaction mixture in the form of a dialkylamine-water solution. The dialkylamines are soluble in water to a high degree, whereas the alkylbromides are not. As a satisfactory alternative embodiment, each of the essential reaction components, i.e., alkylbromide, dialkylamine and water, can be brought together separately into a mixing pump. Provided that sufficient mixing is supplied and provided also that the dialkylamine and the alkylbromide are present in the requisite amounts, the reaction proceeds according to the contemplated method of the present invention.

The reaction mixture prepared according to the manner described above is then heated to initiate the reaction between the alkylbromide and the dialkylamine. This is a highly exothermic reaction and the amount of heat applied to the reaction system should take the factor into consideration. Actually, in this stage of the reaction it is principally the straight chain primary alkylbromide ingredient which reacts with the dialkylamine to form the desired tertiary amine. This is so because the temperature is held to a level in the range of from about 100° F. to about 190° F., and in this temperature the rate of reaction of the straight primary alkylbromide is considerably faster than either of the aforementioned minor alkylbromide components. Beginning with the initial heating at room temperature, e.g., of about 70-80° F., this first reaction stage takes from about 2 to about 7 minutes. In a preferred embodiment, the reaction is conducted at a temperature in the range of from 120° F. to about 170° F. for a period of from about 3 to about 5 minutes, not counting the time required to heat to that temperature range.

As pointed out previously, the reaction between the alkylbromide and the dialkylamine is highly exothermic. It may be necessary, therefore, to provide the reaction system with a heat exchanger to aid in maintaining the reaction temperature in the broad range of 100° F. to 190° F. and preferably in the preferred range of 120° F. to about 170° F.

Strict caution must be exercised to prevent higher temperatures from occurring. Temperatures, for instance, in excess of about 190° F. initiate the formation of undesirable quaternary ammonium compounds and perhaps also tend to cause the formation of color bodies due to localized overheating in the system. The mean temperature in this initial reaction stage over the period of from about 2 to about 7 minutes is about 145° F. Within this period,

e.g., a maximum of about 7 minutes under the prescribed temperature and pressure (see hereinafter), the reaction goes to from about 90% to 95% completion. This completion percentage corresponds to the amount of straight chain primary alkylbromide present as the major component.

As mentioned previously, one of the critical requirements of the present reaction system is maintaining a sufficient pressure within the system to keep the dialkylamine reactant as a liquid. As hereinbefore stated, these pressures can vary from a minimum of about 75 pounds per square inch gauge up to any commercially feasible maximum. Preferred pressure limitations with the preferred dialkylamine, i.e., dimethylamine, are from about 350 pounds per square inch gauge to about 1,200 pounds per square inch gauge.

Under the conditions set forth above for the initial reaction, it is found that the reaction product thereof comprises a major proportion of trialkylamines due to the virtually complete conversion of the straight chain primary alkylbromide to the desired tertiary amine. The remainder of the reaction product is principally the as yet unreacted straight chain secondary alkylbromides, the branched chain primary alkylbromides, dialkylamine, and water. In order to complete the reaction, the reaction product from the initial low temperature reaction is quickly heated to a temperature of from about 275° F. to about 375° F. and held there for a period of from about 4.5 to about 12 minutes. Preferably, the temperature for this high temperature phase of the reaction should be from about 300° F. to about 350° F., and should last from about 5 to about 9 minutes. By practicing the invention in this way, it has surprisingly been discovered that the final reaction product contains only negligible amounts of the undesired quaternary ammonium compounds. Moreover, there is provided yet another major unexpected advantage in that the amount of regenerated olefin is held to an absolute minimum.

The interval between the completion of the first low temperature reaction and the initiation of the high temperature reaction stage should, as a practical matter, be as short as possible. No advantage is gained by interrupting the reaction at this point. In a continuous process, for instance, there need be no delay between these steps, the reaction product passing directly from one stage to the second stage. The high temperature needed for the second stage can be supplied by any means such as a heat exchanger or a heating water or steam jacket. In a continuous process, a heat exchanger is a preferred embodiment, and in a batch reaction system, the reactor vessel can be surrounded with a hot water or steam jacket.

At the conclusion of the second elevated temperature reaction stage, the reaction product is comprised predominantly of a desired tertiary amine, e.g., on the order of about 98%-99%. This reaction product can be directly oxidized to yield an excellent highly effective amine oxide detergent composition.

It should be noted that if temperatures on the order of 300° F. to 350° F. are employed in a single-stage amination reaction system, the reaction product will be seriously adulterated by the presence of regenerated olefins, by quaternary ammonium compounds, as well as other undesired by-products. Moreover, if the amination reaction is performed in a single low temperature stage, the reaction will take a very inordinately long time and even then it will be subject to some of the same disadvantages as a single-stage high temperature reaction.

The reaction product of the high temperature reaction step is comprised of the following reaction products. The major ingredient, of course, is the desired tertiary amine. Since the dialkylamine reactant is added in the large molar excess described earlier, there is still unreacted dialkylamine remaining. Hydrogen bromide is formed as a by-product during the reaction between the alkylbromide and the dialkylamine. The hydrogen bromide forms a salt with

the available excess dialkylamine and is present in that form. Besides these reaction products there can be present in varying but always minor amounts of unreacted alkylbromide, regenerated olefin, and vinylidene branched olefins.

Separation of the desired tertiary amine reaction product can be performed in any devised manner. While not an essential step of the present invention, recovery of the tertiary amine is usually performed by adding a slight excess of sodium hydroxide to the final reaction product. This results in the formation of a brine solution which is then passed to a distillation column where the dialkylamine is stripped off. One convenient way of doing this is by passing steam through the brine solution. The stripped off dialkylamine can be recycled back to the first step of the reaction.

The remaining reaction product is allowed to stand under pressure for a period of time. Two phases gradually appear; the lower phase is essentially trialkyl amines and the upper phase is essentially sodium bromide and water. These phases are easily separated and the sodium bromide is recovered and the water is discarded. The phase containing the tertiary amines is distilled. The distillate is the water-white trialkyl amine.

It is desirable throughout the reaction system to provide for good mixing of the reactants and the reaction mixture. This is especially true in the initial low temperature reaction, but it is desirable also in the second or high temperature reaction.

The process of this invention can be accomplished in both batch and continuous processes. In both cases, however, the particular reaction vessel utilized must be capable of withstanding relatively high pressures and must be capable of effecting a two-step temperature reaction as related above. Furthermore, the batch reaction vessel must be equipped with an agitating device to effect the good mixing which, as mentioned above, is desirable. Suitable reaction vessels for the process of this invention are generally described in Perry's Chemical Engineer's Handbook (3rd edition, 1950), at pages 1256-1258.

The following specific examples are given in order to further explain and illustrate this invention. They are not intended to limit the scope in any way.

EXAMPLE I

The reaction vessel utilized in this example of the above related process was a tubular reactor. The major component of the reactor was a schedule 80 stainless steel pipe of three-quarter inch nominal inside diameter which was 500 feet long. One heat exchanger was provided which permitted gradual heating of the reaction components in the first 100 feet of the reactor. Another heat exchanger was located at 200 feet from the reactor inlet. This heat exchanger permitted rapid heating of the reaction components and products. The entire system was insulated to prevent major heat losses.

Water was continuously metered into a dimethylamine stream so as to form a dimethylamine-water solution containing 15% by weight of water. The dimethylamine-water mixture was then metered into an alkylbromide stream at a molar ratio of dimethylamine to alkylbromide of 17.8:1. The alkylbromide was comprised by weight of 88.8% primary straight chain alkylbromides, i.e., 57.6% 1-bromododecane, 22.3% 1-bromotetradecane and 8.9% 1-bromohexadecane, 3.5% branched chain primary alkylbromides, 5% straight chain secondary alkylbromides, 1.7% paraffins and 1.0 α -olefins. The chain length of the alkyl groups in the alkyl bromide reactant was a mixture of 12, 14 and 16 carbon atoms.

This mixture was introduced into the above-described tubular reactor and heated until the temperature rose to 178° F. The reaction mixture was in a temperature range of 100° F. to 178° F. for about 2.7 minutes. It was maintained at 178° F. for 1.6 minutes. At this point, the temperature of the mixture was abruptly raised to 303° F.

and held there for 4.8 minutes, after which the temperature was again reduced to room temperature.

Throughout the entire reaction, a pressure of about 1000 pounds per square inch was applied to the system to keep the various components in the liquid state. Mild agitation occurred throughout the tubular reactor.

The yield of desired tertiary amine alkyldimethylamine was over 95% based upon the alkylbromide feed stream. The yield of dialkyldimethyl quaternary ammonium bromide impurity was only 0.17% by weight of the total reaction product.

EXAMPLE II

In this example, a reaction vessel similar to that described in Example I was utilized.

Water was continuously metered into a dimethylamine stream so as to form a dimethylamine-water solution containing 13% by weight of water. The dimethylamine-water mixture was then metered into an alkylbromide stream at a molar ratio of dimethylamine to alkylbromide of 13:1. The alkylbromide had the same chain length distribution as in Example I above and was comprised by weight of 88.8% primary straight chain alkylbromides, i.e., 57.6% 1-bromododecane, 22.3% 1-bromotetradecane and 8.9% 1-bromohexadecane, 3.5% branched chain primary alkylbromides, 5% straight chain secondary alkylbromides, 1.7% paraffins and 1.0% α -olefins.

This mixture was introduced into the above-described tubular reactor. During the first 3.2 minutes the temperature was gradually raised from 80° F. to 178° F. The temperature was in a range of 100° F. to 178° F. for about 2.7 minutes. At this point, the temperature was abruptly raised to 326° F. and held there for 4.8 minutes, after which the temperature was reduced to room temperature.

The yield of dialkyldimethyl quaternary ammonium bromide impurity was only 0.13% by weight of the total reaction product. The yield of the desired alkyldimethylamine product was over 95.5% based upon the alkylbromide feed stream.

EXAMPLE III

The reactor described in Example I was utilized for the following runs.

In all of the following runs, a mixture of alkylbromide, dimethylamine and water was prepared. The alkylbromide in all runs was comprised by weight of 93.2% primary straight chain alkylbromides, i.e. 57.2% 1-bromododecane, 22.3% 1-bromotetradecane and 8.9% 1-bromohexadecane, 3.5% primary branched chain alkylbromides, 5% secondary alkylbromides, 1.7% paraffins and 1.0% α -olefins.

This mixture was introduced into the above-described tubular reactor. During the first 3.2 minutes, the temperature was gradually raised from 80° F. to 178° F. At this point, the temperature was abruptly raised to 326° F. and held there for 4.8 minutes, after which the temperature was reduced to room temperature.

The yield of dialkyldimethyl quaternary ammonium bromide was only 0.13% by weight of the total reaction product. The yield of alkyldimethylamine was over 95.5% based upon the alkylbromide feed stream.

EXAMPLE IV

The reactor described in Example I was utilized for the following runs.

In all of the following runs, a mixture of alkylbromide (the alkyl group being a mixture of C_{10} to C_{18} carbon atoms, predominantly C_{12} to C_{16}) dimethylamine and water was prepared. The alkylbromide in all runs was comprised by weight of 93.2% straight chain primary alkylbromides, 2.5% branched chain primary alkylbromides, 3% secondary alkylbromides, 1.2% paraffins and 0.1% α -olefins. The procedure followed in Example I was followed herein. The results of four runs are tabulated below.

TABLE 1

	Run 1	Run 2	Run 3	Run 4
1. Percent water in dimethylamine-water solution.....	12	14	12	15
2. Mol ratio of dimethylamine to alkylbromide.....	12:1	12.5:1	13.5:1	12.5:1
3. Temperature during first 3.2 minutes,* ° F.:				
A. Beginning.....	80	80	80	80
B. End.....	190	190	175	180
4. Temperature during last 4.8 minutes, ° F.....	340	340	340	340
5. Percent dialkyldimethyl ammonium bromide impurity by weight of reaction product.....	0.21	0.40	0.52	0.19

*It takes about .5 minute to get from room temperature to 100° F.

Temperatures in (3) in the above table are part of initial reaction of the heretofore discussed process. Temperature shown in (5) above are representative of the second stage of the process.

In all cases, excellent results were obtained. As can be seen from Table 1, the highest incidence of dialkyldimethyl ammonium bromide impurity was 0.52%. In all cases, over 95% of the reaction product was desired trialkylamines.

EXAMPLE V

The reaction vessel utilized in this example was a 1-gallon batch reaction vessel capable of withstanding a pressure up to 1,000 pounds per square inch gauge. This reaction vessel was fitted with a stirring device and thermometer.

The dimethylamine-water solution containing the percentages of water shown in Table 2 were placed in the reactor and heated to the temperature specified in the table below. Alkylbromide (the alkyl group being a mixture of C_{10} to C_{18} carbon atoms, predominantly C_{12} to C_{16}) comprised by weight of 93.2% primary straight chain alkylbromide, 2.5% primary branched chain alkylbromides, 3% secondary alkylbromide, 1.2% paraffins and 0.1% α -olefins, was heated outside the reactor and injected into the batch reactor in the hereinafter stated mol ratio of dimethylamine to alkylbromide. The reaction was allowed to proceed under nearly adiabatic conditions under which the temperature of the reaction stabilized. The temperature was then increased to 300° F. for 9 minutes.

TABLE 2

	Run 1	Run 2	Run 3
1. Percent water in dimethylamine-water solution.....	10	10	10
2. Mol ratio of dimethylamine to alkylbromide.....	9.0:1	16.9:1	16.7:1
3. Temperature at beginning of reaction.....	110	110	150
4. Time, in minutes, before temperature was raised.....	5	5	3
5. Time in minutes at 300° F.....	9	9	9
6. Percent dialkyldimethyl ammonium bromide by weight of reaction product.....	0.40	0.10	0.15

As can be seen from the above table, the percentage of dialkyldimethylammonium bromide was in all cases less than 0.40%. Over 95% of the reaction product was trialkylamine.

In the foregoing examples, other of the alkylbromides and dialkylamines, e.g., diethylamine, in the respective ranges hereinbefore mentioned, can be substituted for the

ones specifically mentioned. Additionally, the amounts of each component can be varied within the ranges delineated in the foregoing discussion. Likewise, the residence time in the reactor and the temperature of the reaction can be varied within the limits discussed previously.

The foregoing description of the invention has been presented describing certain operable and preferred embodiments. It is not intended that the invention should be so limited since variations and modifications thereof will be obvious to those skilled in the art, all of which are within the spirit and scope of this invention.

What is claimed is:

1. A process for preparing trialkylamines comprising the steps of
  - (1) preparing a reaction mixture containing an alkylbromide, said alkylbromide comprised of a major proportion of straight chain primary alkylbromides and a minor portion of straight chain secondary and branched-chain primary alkylbromides wherein the alkyl group of said alkylbromides contains from about 10 to about 20 carbon atoms; and a dialkylamine-water solution comprising a dialkylamine wherein the alkyl groups contain from 1 to about 3 carbon atoms; said dialkylamine-water solution containing from about 5% to about 20% water by weight; the molar ratio of said dialkylamine to said alkylbromide in said reaction mixture being in excess of about 8:1;
  - (2) reacting said alkylbromide with said dialkylamine for from about 2 to about 7 minutes at a temperature of from about 100° F. to about 190° F. and under sufficient pressure to maintain said dialkylamine in a liquified state to form a reaction product;
  - (3) thereafter heating said reaction product to a reaction temperature of from about 275° F. to about 375° F. for from about 4.5 to about 12 minutes and under sufficient pressure to maintain the dialkylamine in a liquified state.
2. The process of claim 1 wherein the molar ratio of dialkylamine to alkylbromide is from 12:1 to 18:1.
3. The process of claim 1 wherein said dialkylamine-water solution contains from about 8% to about 15% water by weight.
4. The process of claim 1 wherein the alkyl group of the said alkylbromide contains from about 12 to about 16 carbon atoms.
5. The process of claim 1 wherein the residence time in step 2 is from about 3 to about 5 minutes at a temperature of from about 120° F. to about 170° F. and the residence time in step 3 is from about 5 to about 9 minutes at a temperature of from about 300° F. to about 350° F.
6. The process of claim 1 wherein the dialkylamine is dimethylamine.
7. The process of claim 5 wherein a pressure of from about 350 to about 1200 pounds per square inch gauge is applied to the system.
